CORRUGATED-FASTENER MACHINE

Albert E. Cranston, Wenatchee, Wash.

Application November 18, 1935, Serial No. 50,371
In Canada March 13, 1935

9 Claims. (CL 1—8.1)

This invention relates to improvements in fastener driving machines and it has reference in particular to machines for attaching together board pieces by means of devices known in trade as "corrugated fasteners"; the present invention having for its principal object to provide means whereby paired, or complementary, board pieces of various widths may be advanced from a supply hopper and brought tightly together in edge to edge abutment and in proper alignment with the fastener applying devices for the reception of the fasteners.

Explanatory to the present invention, it will here be stated that in the present day manufacture of apple boxes, and the like, the end sections of the boxes instead of being made from single pieces of board, can be economically made up of two board pieces secured edge to edge to form an end section of the standard dimension which is approximately 12 inches square. Sometimes two pieces of equal width are used to form an end section, but more frequently the pieces are of unequal width; it being essential only that the two pieces used be of the required length and that their combined widths, when assembled, equal the width of an end section of the standard dimensions. Thus, it may be that in the promiscuous selecting of board pieces for a box end, a board seven inches wide will be assembled with one five inches wide. The next end assembled may comprise a board piece four inches wide associated with one eight inches wide, and the next end to be assembled may comprise pieces of still different widths. Heretofore, it has been customary to manufacture box ends employing two pieces, as in the present case, and to fasten the complementary pieces together by means of corrugated fasteners applied across the joint, but in such cases an operator has always manually assembled the pieces and has manually located them properly with respect to the fastener driving machine for reception of the fasteners. Manual assembly and placement of the pieces, however, is not entirely satisfactory, principally for the reason that it decreases speed of production and furthermore, it adds expense to manufacturing costs by reason of the labor involved.

In view of the above statement of disadvantages incident to manual placement of parts in the fastener driving machine, it has been the principal object of this invention to provide a machine for the mechanical assembling of complementary board pieces for the manufacture of box ends. Furthermore, to provide a machine including a divided hopper within which the com-

plementary board pieces to be made into box ends may be stacked, and to provide a practical and novel means whereby the complementary parts in random stacking may be brought together and delivered to the fastener machine and the joint thereof accurately located for reception of the fastener devices regardless of variation to the machine.

It is also an object of this invention to provide a novel arrangement of feed rolls whereby the complementary parts for individual box ends may be brought tightly together coincident with their advancement to the fastener machines in a joint that will be located in proper alignment for reception of the fasteners.

Another object resides in the provision of means for applying fasteners from opposite sides of the board.

Other objects of the invention reside in the various details of construction; in the combination of parts, and in their mode of operation, as will hereinafter be described.

In accomplishing these and other objects of the invention, I have provided the improved details of construction, the preferred forms of which are illustrated in the accompanying drawings wherein—

Fig. 1 is a side elevation of a machine embodying the present invention.

Fig. 2 is a cross sectional detail through the divided hopper of the machine, particularly illustrating the arrangement relative to the hopper partition, of the board pieces from which the box ends are made.

Fig. 3 is a perspective view of a box end comprising complementary board pieces joined by means of corrugated fasteners in accordance with the present invention.

Fig. 4 is a plan, or top view of the machine.

Fig. 5 is a cross sectional detail on the line 5—5 in Fig. 4, illustrating the manner of mounting the rolls.

Fig. 6 is an enlarged plan view of the series of paired rolls whereby the complementary board pieces are crowded together incident to advancement from the hopper to the fastener machine.

Fig. 7 is a transverse section, in a vertical plane, particularly illustrating the relationship of upper and lower rolls; parts being broken away for better illustration.

Fig. 8 is a central longitudinal section of the machine as seen in line 8—8 in Fig. 4.

Referring more in detail to the drawings—
The frame structure of the present machine preferably is of angle iron formation, and it

comprises a horizontal top plate 1 forming a bed or table, and this is supported by opposite end frames 2 and 3 that are joined across their lower ends by connecting rails 4. Mounted above the table, approximately midway between its ends, and supported from the opposite side edges thereof, by frames or brackets 5a, is a hopper 5. This comprises a vertical front wall 6, an inclined back wall 7, and a central partition wall 8 extending in the longitudinal direction of the machine. The board pieces, to be assembled to form the box ends, are stacked in the hopper upon the table, at opposite sides of the partition wall, as shown in Fig. 2, and in such order that complementary pieces may be simultaneously advanced from the lower end of the hopper to the fastener driving machines, as presently will be described.

In stacking the pieces of board in the hopper, the complementary parts for the individual box ends are arranged at opposite sides of the partition wall, as will be noted by reference to Fig. 2, and this arrangement provides that incident to feeding, the lowermost pieces always will be paired for the formation of a box end. Complementary pieces need not be of the same size and it is usual that they are of unequal widths. Also, the widths of pieces of successive ends in the hopper may vary considerably as is apparent in Fig. 2.

30 In the present machine, there are two fastener driving heads operating in unison and they are located in advance of the hopper, respectively, above and below the table. In Fig. 8, the two heads are designated by reference numerals 10-10', and they are located in longitudinal spacing that the board pieces may be advanced in succession thereto to receive the fasteners, and the location of these heads 10-10' is such that the fasteners will be driven into the boards in 40 symmetrical spacing. The sections of board, when fastened together, assume the relationship illustrated in Fig. 3, wherein —a— and —b— designate the complementary board pieces and c designates the fasteners driven from the top 45 side and d the fasteners driven from the under side.

50 The means which have been provided for simultaneously advancing the complementary board pieces from the hopper to the fastener driving machines comprises a pair of chain belts, 12 and 12', which operate about paired sprocket wheels 13 and 13', located at opposite ends of the main frame and supported, respectively, by cross shafts 14 and 14'. The top runs of the two belts operate longitudinally along the table top at opposite sides of the hopper. Secured to these chain belts, at regularly spaced intervals, are transverse feed bars 15, which, incident to travel of the chains, pass through the lower end of the hopper thereby to simultaneously engage and advance the two lowermost pieces of boards in the hopper and forward them to the fastener driving machines. Upon advancement of each set of boards from the hopper, the two stacks of board pieces 60 feed downwardly by gravity and the lowermost pieces in the stacks come into position for advancement by the next oncoming cross bar 15.

70 It will be observed, by reference to Fig. 8, that the lower edge of the front wall of the hopper terminates in such spacing above the supporting table that but one set of boards can be advanced at a time. Vertical adjustment of the wall in any suitable way may be provided to accommodate boards of different thickness.

75 The advancement of the feed chains is inter-

mittent and the interval of advancement is exactly such that the boards, at periods of rest, will be properly disposed relative to the driving heads 10-10' to receive the fasteners. Successive advance movements of the boards after leaving the hopper places them in position to receive the fasteners from the driving head 10 near opposite edges in to upper face, and on the next advance movement, the boards are properly located to receive the fasteners from head 10' centrally in its under side.

5 15 20 25 30 35 40 45 50 55 60 65 70 75 80 85 90 95 100

Advancement of the sprocket wheels is effected by an intermittent advancement of the shaft 14. This shaft is revolvably mounted in supporting bearings 16 and at one end has a ratchet 17 fixed thereon. Adjacent the ratchet, a lever arm 18 is revolvably mounted on the shaft and this has a pawl 19 pivoted thereon to engage and advance the ratchet in one direction. Mounted transversely of the frame in supporting bearings 20 is a driven shaft 21 equipped at one end with a belt pulley 22 for a driving belt.

As illustrated best in Fig. 8, the transverse shaft 21 is the main drive shaft of the fastener driving head 10', and the driving head 10 has a main drive shaft 50. The shaft 50 is driven by a chain belt 52 that extends about sprocket wheels 53 and 54, secured respectively on the shafts 21 and 50, and it is to be observed that the sprocket wheel 50 is but one-half the diameter of wheel 53, providing that the lower head will drive one fastener to two driven by the upper head for apparent reasons.

On one end of shaft 50 is a crank arm 23 connected by a link 24 with the lever arm 18 in a manner whereby each rotation of the crank effects a definite advancement of the ratchet and thereby a definite advancement of the feed chains. The link is connected pivotally to arm 18 by a bolt 25 and the bolt may be adjusted along the lever arm to lengthen or shorten the intermittent advancements of the feed chains.

It will be apparent that the random stacking of the board pieces in the hopper at opposite sides of the partition is rather irregular and does not bring paired pieces tightly together for reception of the fastener devices. Therefore, a feature of this invention resides in the provision of means for bringing the complementary pieces of board tightly together and in the provision of means for registering the joint of each set of pieces to be joined properly with reference to the fastener machines so that the fasteners, when driven, will be embedded equally in the two pieces of board, and there will be no open joint. This means is as follows:

Forwardly of the hopper there is arranged a series of pairs of assembling rolls across which the board pieces are advanced and whereby the complementary pieces of board will be crowded together. The location of these rolls, relative to the hopper and fastener machines is shown in plan view in Fig. 4, and the rolls are shown in enlarged plan view in Fig. 6. The three pairs of rolls, designated at 30-30', 31-31', and 32-32' are arranged in a recess in the table in a row longitudinally thereof, and symmetrically at opposite sides of the plane of a vertical, registering fin 33 which is attached to the forward wall of the hopper 8 and aligned with the plane 70 of the partition wall 8 of the hopper; its lower edge being spaced above the plane of the table across which the boards are advanced, as is shown in Figs. 7 and 8. The rolls are all of the same size and their supporting axles 34 are all 75

horizontally disposed and are fixed in supporting brackets 36, attached to a plate 37, underlying and suspended from the table, as illustrated in Fig. 7. The top surfaces of the rolls are above the surface of the table and the axles of paired rolls are set in the same angular relationship to each other, and also with respect to the line of travel of the board pieces so that when the complementary pieces of board are advanced from the hopper to travel respectively upon the rolls at opposite sides of the fin 33, they will be crowded toward each other. It is to be observed, however, by reference to Fig. 7, that the rolls at one side of the alignment fin 33 are set somewhat higher in elevation than those at the other side, thereby to cause the board pieces that pass across the higher rolls to contact the side of the lower edge of the fin while those that are advanced by the other rolls do not contact the fin but are urged over into contact with the opposite pieces. Thus the two pieces of board, when they arrive at the staple driving head, are in close contact.

In order to insure this crowding together of the two pieces of board, a pair of pressure rolls 40-40' are provided, respectively, to overlie the rolls 30-30', see Figs. 7 and 8, which are the first pair of lower rolls. These pressure rolls are mounted at the lower ends of plungers 41 which are slidably contained in vertical guide tubes 42 fixed to a transverse channel bar 43 overlying the table between the brackets 5a. Springs 45 are arranged within the tubes to bear downwardly against the plungers thereby to yieldingly urge the pressure rolls against the boards. The downward movement of the pressure rolls is limited by means of pins or studs 46 which are fixed in the plungers and extend into longitudinal slots 48 in the guide tubes. The pressure rolls are arranged in the same angular relationship as are the rolls below them, and they aid in the inward crowding of the pieces against the fin 33. Also, by the adjustment of tension adjusting screws 45A in the upper ends of the tubes 42, the pressure of the rolls 40' may be made greater than rolls 40, thereby to insure that the boards which are contacted by the rolls 40 will not crowd the other boards away from the fin. This result might also be obtained by adjusting the rolls to different angular relationship relative to the line of travel.

The corrugated fastener driving heads 10-10' may be of any suitable kind. However, a preferred construction of machine is one in which means is provided for the feeding of a strip of corrugated fastener material to a reciprocating cutter which operates in timing with the feed chains to cut a fastener of a definite length from the strip and to place the piece in the path of a reciprocating hammer which drives it into the edges of adjacent board sections. The two driving heads, as here illustrated, are arranged above and below the table, and are in proper spacing for the particular work being done, and they are so aligned that the fasteners will be driven in the proper position.

As a matter of construction, the head 10 is supported by a horizontal arm 60 extending transversely of the main frame from the upper end of a vertical post 61. This post is vertically adjustable in a base standard 62 to accommodate boards of different thickness.

The head 10' is supported by a vertical post 65 fixed to the frame structure as seen in Fig. 1, and the post 62 is adjustable in its spacing from

post 65 to change the spacing of the fasteners in their application to a board.

In the illustration of the fastener driving heads, as shown in Fig. 8, it is apparent that the two heads are alike in construction, but the lower one is inverted so as to drive its fasteners into the under sides of the boards. This necessitates an abutment to back up the boards, and such an abutment is shown in the form of a cross bar 68, supported adjustably from a cross beam 69, mounted transversely of the frame and supported above the table. Likewise, a supporting bar 70 is arranged below the table below the driving head 10.

Each of the driving heads, as shown in Fig. 8, comprises cams 75 and 76 fixed in the main drive shafts and these, respectively, actuate the fastener driving hammer 77 and a lever 78 which reciprocates the fastener cut-off and positioning slide; a detailed description of which is disclosed in my U. S. application Serial No. 10,835 covering this particular head.

Assuming the machine to be so constructed, it is operated as follows:

First, the complementary board pieces are stacked in the hopper. Then, upon starting the machine, complementary pieces are advanced together from the hopper across the crowding rolls, whereby the pieces are brought tightly in edge to edge contact as they advance beyond the fin 33. This fin locates the joint exactly in the line of travel for proper reception of the fastener devices. The intermittent movement of the feed chains first brings the forward edge of the boards below the driving head 10. The next movement brings the rearward edge into position. The next advance movement locates the board properly above the head 10' to receive the fastener from the under side. Repeated intermittent advance movements carry the boards through the machine and they are delivered, properly fastened, for use.

Various adjustments are provided to accommodate the machine to boards of different thicknesses, and adjustment can be made in the driving heads for fasteners of different dimensions. These parts are not important features of the invention. However, they permit a better and more extensive use of the machine.

The main features on which patent protection is desired reside in the novel arrangement of the series of crowding rolls for bringing the board pieces tightly together in their advancement to the driving heads, and in the arrangement of the heads for a different location of the fastener devices, both with respect to its top and bottom surfaces.

Having thus described my invention, what I claim as new therein, and desire to secure by Letters Patent is—

1. In a corrugated fastener applying machine, the combination with a fastener driving head, a hopper for complementary board pieces, and means for conveying complementary board pieces simultaneously to the driving head, of a guide fin aligned with the head, a series of rolls arranged at each side of the fin, for conveyance of the board pieces thereacross by the advancing means and angularly disposed with reference to the direction of travel of the pieces, and whereby the pieces will be held together and advanced while one is held in guiding contact with the fin.

2. In a corrugated fastener driving machine, the combination with a fastener driving head, a hopper for board pieces, and a conveyer for simul-

5 taneously conveying complemental board pieces to the driving head, of a joint registering fin aligned with the head, a series of rolls arranged in the path of conveyance of the board pieces and across which they respectively will be conveyed; said rolls being mounted in angular relationship whereby the pieces are caused incident to conveyance thereover to be crowded together in edge to edge abutment, and the joint aligned 10 with the fastener driving head for reception of a fastener; one set of rolls being positioned to cause the inside edge of one of the board pieces to be held against the fin for guidance thereby while advancing.

15 3. A combination as recited in claim 2 wherein means is provided in connection with the rolls at opposite sides of the fin for applying pressure downwardly against the boards while conveyed across the said rollers and means for varying the 20 pressure of the two means.

25 4. In a corrugated fastener driving machine, a fastener driving head, a hopper for complemental board pieces, a conveyer whereby complemental pieces are simultaneously advanced from the hopper to the driving head, a joint registering guide plate aligned with the driving head and disposed for the conveyance of the complemental board pieces at opposite sides thereof, and a series of freely revoluble rolls mounted at opposite sides 30 of the plate for the advancement of the board pieces thereacross, said rolls being angularly disposed relative to the plate, thereby to cause one of the board pieces to be crowded against the plate for aligning the joint with the fastener 35 driving head and the other board to be held against the aligned board.

40 5. In a corrugated fastener driving machine, a fastener driving head, a hopper for complemental board pieces, a conveyer whereby complemental pieces are simultaneously advanced from the hopper to the driving head, a joint registering guide plate aligned with the driving head and disposed for the advancement of the complemental pieces at opposite sides thereof, and a series of freely revoluble rolls mounted at opposite sides 45 of the plate for the conveyance of the board pieces thereacross; said rolls being angularly disposed relative to the plate, thereby to cause the board pieces incident to conveyance 50 thereover, to be crowded together and one to be held in guiding contact against the plate for aligning the joint with the fastener driving head, and pressure rolls arranged in the same angular

relationship as the lower rolls, for bearing downwardly against the board pieces while being conveyed on the first mentioned rolls.

6. In a machine of the character described, a fastener driving head, a hopper in which stacks 5 of complemental board pieces for box ends may be contained, a dividing partition in the hopper between the stacks of complemental pieces and a registering guide plate extending forwardly of the hopper in the plane of the partition, means 10 for advancing complemental board pieces from the lower end of the hopper to the fastener driving head, and a series of rolls arranged at opposite sides of the registering plate across which the boards will be advanced; said rolls being located 15 in angular relationship axially relative to the plate to effect the crowding of the board pieces together and against the plate in their advancement across the rolls, and yieldable means exerting downward pressure against the board 20 pieces while passing across the rolls and an adjustment means for each pressure roll.

7. In a machine of the character described, the combination with a hopper for complemental board pieces, a conveyer for advancing complemental pieces together, by intermittent movements, through the machine, a fastener driving head arranged above the path of travel of the boards, a second machine arranged below the path of travel, and means for operating the machines in timing with the intermittent advance movements of the boards for the application of fasteners to the top and lower surfaces thereof. 30

8. A machine as recited in claim 7, wherein the fastener driving machines above and below the path are spaced in the longitudinal direction of travel, and are timed to provide that the upper machine drives its fasteners at opposite ends of the board, and the lower machine locates its fasteners at an intermediate point in the under 40 side of the board.

9. In a board feed mechanism, a conveyer mechanism whereby board pieces are advanced simultaneously at opposite sides of a registering guide plate, and a series of rolls arranged at opposite sides of the plate at different elevation and upon which the boards are conveyed, and in angular axial relation whereby to cause the board pieces to be crowded together and one against the plate and brought into edge to edge abutment 50 upon advancement beyond the plate.

ALBERT E. CRANSTON.
